ARC RUPTURING DEVICE FOR ELECTRIC SWITCHES

Emil Lange, Berlin-Zehlendorf, Germany

Application December 10, 1935, Serial No. 53,749
In Germany December 10, 1934

3 Claims. (Cl. 200—150)

This invention relates to an electric switch of the kind wherein means are provided for rupturing an arc, formed between the switch contacts, by a blast or jet produced on the heating by the arc itself of a fluid contained in an adjacent chamber.

The object of the invention is to provide means for maintaining the blast itself as cool as possible in order to ensure a reliable rupturing of the arc, and the invention consists essentially in the provision of means for forming one arc at the outlet of a chamber and another arc inside a bell in said chamber which communicates with the outlet through a circuitous route, so that the pressure produced by the heating of the fluid in said space, will cause the comparatively cold fluid in the principal space of the chamber, to be ejected through the outlet and to rupture the arc at the latter, means being provided for preventing the fluid inside the bell from mixing with the fluid at the outside thereof.

The confined space for the second arc may be formed by a bell supported within the chamber with the crown turned towards the outlet.

Figs. 1-4 of the accompanying drawing are sectional views of different forms of a switch constructed according to the invention.

Each of the illustrated switches comprises a chamber 1 having at one end an outlet 5 which is closed by a spring-controlled valve 6 adapted to open at a given pressure of the gas or other fluid and closed in the chamber. The switch has a rod-shaped actuating contact 3 which is movably mounted in the end of the chamber situated opposite the outlet 5. In the arrangement shown in Figs. 1 and 2 the chamber contains a bell 7 which is slidably mounted by means of holded lugs 9 on guide rods 8 and controlled by springs 11. In the crown of the bell an auxiliary contact 4 is mounted which is formed inside the bell as a socket for the reception of the rod 3. Outside the bell the contact 4 has the form of a pin provided with a bevelled end which, in the construction according to Fig. 1, is adapted to engage a principal, annular contact 2 fitted in the outlet of the chamber. Adjustable collars 10 on the rods 8 support the bell in opposition to the springs 11 and co-operate with the latter for maintaining the end of the auxiliary contact 4 normally at arc 50 producing distance from the principal contact 2.

The operation is as follows:

For closing the switch, the rod 3 is advanced so as to engage the auxiliary contact 4 and press it against the principal contact 2, the bell being advanced together with the contact 4 in opposi-

tion to the springs 11. On the rod 3 being retracted for breaking the circuit, the auxiliary contact recedes and forms an arc between it and the principal contact 2. The contact 3 also leaves the contact 4, and a second arc is formed between these contacts inside the bell. The fluid inside the bell becomes heated by the arc and sets up a pressure which is communicated to the space outside the bell and which eventually causes the valve 6 to open. The escaping fluid traverses the arc and forms a blast by which the arc will be ruptured. Since the blast is composed of the comparatively cold fluid contained in the chamber 1 outside the bell 7, a reliable rupture of the arc will be ensured.

The arrangement shown in Fig. 2 operates in the same manner but differs from the arrangement of Fig. 1 in that the principal contact has the form of a rod 12 which forms a stem for the valve disc 6' by means of which the outlet is normally closed. The contacts 4 and 12 meet within a ring 2' which ensures a good electric connection.

Fig. 3 shows an arrangement wherein the bell 7' is rigidly connected to the chamber 1 by means of radial arms 13 which may be integral with the two elements. The auxiliary contact 4' is slidably arranged in the bell and controlled by a spring 13. Otherwise the construction and action are the same as described in connection with Fig. 1.

In order to ensure that the hot fluid from the bell shall not reach the outlet 5, means may be provided for separating the fluid in the bell from that of the outside space. Such an arrangement is shown in Fig. 4. The bell 7'' is in this case connected at the base to the chamber 1 and formed at the base with slots through which it communicates with the chamber. Arranged in the space between the bell and the chamber is an annular piston 15 which separates the fluid in the bell from that of the principal chamber space. When the pressure in the bell increases, the piston will be thrust forwards and will act on the fluid outside the bell for rupturing the arc at the outlet as previously described. The chamber 1 is provided with additional outlet ports 16 which are normally closed by the piston and which are eventually uncovered thereby as it is moved forwards by the pressure, so that the hot gas can escape through the ports. Between the chamber wall and the projection 14 formed around the outlet, an annular space 18 is formed for the reception of the piston 15. The air which is trapped in this space serves as a buffer for the

piston and prevents shocks. The piston movement may be positively limited by abutments 17 on the bell 7".

The arc rupture may be effected either by means 5 of a liquid or a gas, and the valve which normally closes the outlet 5 may be omitted.

I claim:

1. An electric switch of the character described, comprising a closed chamber containing a fluid 10 and having an outlet for the latter, a spring-pressed closing member for said outlet, a principal contact arranged in said outlet, a bell supported within said chamber, an actuating contact movably mounted in the chamber and located 15 within the bell, a movable auxiliary contact mounted in the crown of the bell in position to co-operate with the principal contact as well as with the actuating contact, means for preventing the fluid inside the bell from mixing with the fluid 20 at the outside thereof, and means tending to maintain the auxiliary contact at arc forming distance from the principal contact, the actuating contact being operative to press all the contacts together for closing the circuit and to form an arc inside the bell on the circuit being broken for driving fluid from outside the bell through the outlet and rupturing the arc in the latter.

2. An electric switch of the character described, comprising a closed chamber containing a fluid 30 and having an outlet for the latter, a spring-pressed closing member for said outlet, a principal contact arranged in said outlet, a bell supported within said chamber, an actuating contact movably mounted in the chamber and located 35 within the bell, a movable auxiliary contact mounted in the crown of the bell in position to co-operate with the principal contact as well as with the actuating contact, an annular piston

movable in the space between the bell and the chamber wall and operative to prevent the fluid inside the bell from mixing with the fluid at the outside thereof, and means tending to maintain the auxiliary contact at arc forming distance 5 from the principal contact, the actuating contact being operative to press all the contacts together for closing the circuit and to form an arc inside the bell on the circuit being broken for driving fluid from outside the bell through the outlet and 10 rupturing the arc in the latter.

3. An electric switch of the character described, comprising a closed chamber containing a fluid and having an outlet for the latter, a spring pressed closing member for said outlet, a principal contact arranged in said outlet, a bell supported within said chamber, an actuating contact movably mounted in the chamber and located within the bell, a movable auxiliary contact mounted in the crown of the bell in position to 20 co-operate with the principal contact as well as with the actuating contact, an annular piston mounted in the space between the bell and the chamber and capable of being shifted by fluid pressure in the bell, the chamber being provided 25 with additional outlet ports normally closed by the piston and arranged in position to be uncovered on the piston being shifted from its normal position, and means tending to maintain the auxiliary contact at arc forming distance from the 30 principal contact, the actuating contact being operative to press all the contacts together for closing the circuit and to form an arc inside the bell on the circuit being broken for driving fluid from outside the bell through the outlet and 35 rupturing the arc in the latter.

EMIL LANGE.
